FIG. 6.

FIG. 4.

UNITED STATES PATENT OFFICE.

ALFRED G. F. KUROWSKI, OF NEW YORK, N. Y., ASSIGNOR TO UNDERWOOD TYPE-WRITER COMPANY, OF NEW YORK, N. Y., A CORPORATION OF DELAWARE.

TYPE-WRITING MACHINE.

1,144,766.

Specification of Letters Patent. Patented June 29, 1915.

Application filed January 9, 1912. Serial No. 676,136.

To all whom it may concern:

Be it known that I, ALFRED G. F. KUROWSKI, a citizen of the United States, residing in Brooklyn borough, in the county of Kings, city and State of New York, have invented certain new and useful Improvements in Type-Writing Machines, of which the following is a specification.

This invention relates to typewriting machines in which a relative shifting movement is effected between the types and the platen, to enable either lower case or capital letters to be written, and particularly to those machines in which the platen remains stationary while the type-bars are shifted up and down.

One of the main objects of the invention is to provide an improved connection between the type-bars and the key levers which extend rearwardly under the type-bar segment, whereby the type-bars are permitted to shift up and down while remaining connected to the key levers.

I provide between the type-bars which are mounted upon a shifting segment, and the key-operated bell cranks, which are mounted upon the framework of the machine, a series of individual slides, which have pin-and-slot connections to the type-bars, for the usual purpose, and which also have pin-and-slot connections to the bell cranks to permit relative play of these members during the printing strokes, and also to permit up-and-down shifting of the type-bar segment for printing capital and lower case letters.

In another case, Serial No. 776,008, filed June 27, 1913, a division of the present case, I have claimed the means whereby the type-bar segment may be shifted.

Another object is to improve the means for shifting and guiding the type-bar segment.

Other features and advantages will hereinafter appear.

In the accompanying drawings, Figure 1 is a sectional side elevation showing a type-bar and connected parts in printing positions; the shiftable segment being in its lower-case position. Fig. 2 is a sectional side elevation, taken about midway from front to rear of an Underwood typewriting machine, modified according to the present improvements; the parts being shown in nominal positions. Fig. 2^a is a fragment of one of the slotted portions of the type-

bar-segment, to illustrate the arrangement therein of the fulcrum rod for the type-bars and the guide rods for the type-bar driving slides. Fig. 3 is a view similar to Fig. 1, but showing the parts shifted up for writing capitals. Fig. 4 is a sectional front view of the type-bars, type-bar segment and connections. Fig. 5 is a diagrammatic sectional front view of the type-bar, the bell crank and the connection between them. Fig. 6 is a side elevation of one of the guides for the shiftable type-bar segment. Fig. 7 is a perspective of a type-bar and its connection to a bell crank. Fig. 8 is a sectional view to illustrate the method of taking up play in a type-segment guide. Fig. 9 is a sectional front elevation of the right-hand portion of the type-segment and the adjustable guide therefor.

Type-bars 1 are pivoted upon a common fulcrum wire 2, and guided in radial slots 3 in a segment 4, to strike upwardly and rearwardly against the front side of a platen 5. Said type-bars normally rest upon a pad 6, supported by a basket 7 on rods 8 extending forwardly from said segment 4. Each type-bar carries a lower case type 9 and a capital type 10. The type-bar segment is shifted upwardly by means of a shift key 11, mounted on the forward end of a lever 12, which has an arm or hook 13 to engage and depress a wrist 14 fixed upon a crank 15 projecting forwardly from a horizontal rock shaft 16, which extends across the machine beneath the type-bar segment 4, and is journaled at its ends in lugs 17, Fig. 4. There are two of the shifting levers 12, see Fig. 4. Said rock shaft 16 carries a pair of arms 18 at opposite sides of the machine, said arms slotted to engage wrists 19 projecting from legs 20 of the type-bar segment; said legs depending from an elevated cross-bar 21, to which the segment proper is attached by screws 22; said legs occupying positions one on either side of the segment 4, as at Fig. 4.

In each of the arms 18 is a cam slot 23. These slots are engaged by the wrists 19. As seen at Fig. 1, the wrists 19 normally occupy dead or dwell portions 24 in the forward ends of the slots, to lock the segment against lifting; this portion 24 of the slots being substantially concentric with the shaft 16, for this purpose. It will also be seen at Fig. 3 that the opposite end of the slot 23

also terminates in a dead or dwell portion 25, thereby locking the segment in its upper position, so that there can be no shake thereof; this portion of the slot being also 5 substantially concentric though with a longer radius to the shaft 16. Upon the framework are opposite stop lugs 26 to engage upper and lower stops 27, 28, secured upon each of the legs 20, to arrest the segment when shifted in either direction. The lugs 26 have vertical slots 26^a engaged by screws 26^b, which adjustably fasten the lugs to the legs, the adjustment being determined by the throw of the slotted arms 18.

15 The segment is guided by pairs of rolls 29, each pair comprising an upper and a lower roll journaled to a vertical carriage 30 and occupying vertical grooves 31, 32, the grooves 31 formed in the outer 20 sides of the legs 20, and the grooves 32 formed in the inner sides of a pair of plates 33 secured upon the opposite sides of the framework. Each groove has converging or V walls 34, Fig. 8, and the ends of 25 the rolls are coned to fit these converging walls.

The plate 33 is adjustable toward the leg 20 at Figs. 8 and 9, to adjust it to the rolls, and take up play. The plate has a vertical 30 tongue 35 to fit in a groove 36 in a part 37 of the framework of the typewriter. By means of upper and lower screws 38 and intermediate screws 39, the plate 33 may be 35 adjusted toward the left at Fig. 9 to tighten the rolls 29, the latter having clearance at their ends, as shown at Fig. 8, to insure that they will always fit. The screws 38 are threaded into the fixture 37 and bear against the tongue 35, and the screws 39, 40 which are threaded into the tongue 35, may be tightened, drawing the tongue firmly against the tips of the screws 38. Each carriage 30, to which the rolls are journaled by 45 pintles 40, has a lug 41, at its upper end, to catch upon the top of the plate 33, to support the carriage in normal position.

Upon the shaft 16 is a coiled spring 42, which partly counterbalances the weight of the segment and type-bars; the latter returning 50 by gravity to normal position. A returning spring 43 is connected to one of the arms 18.

The type operating keys are designated as 44, and are mounted upon levers 45 somewhat similar in form to the levers 12, and fulcrumed on the same bar 46, and having 55 similar returning springs 47. Upon the levers 45 are wrists 48 to engage slots 49 in the horizontal arms 50 of a set of bell 60 cranks, the latter also comprising upright arms 51 having wrists 52 to engage slots 53 extending up and down in arms 54 provided upon slides 55, the latter having wrists 56 to engage slots 57 in the type bars 1, to 65 swing them up to print, (Fig. 1).

The slot 53 extend up and down in the direction in which the type bar segment is shifted, and is long enough to accommodate such shifting movement, so that the stationary bell cranks 51 remain connected to the 70 type bars when they are elevated to print capital letters as at Fig. 3.

The bell cranks are indicated diagrammatically in front elevation at Fig. 4, and it will be seen that between their ends nearly 75 all of the bell cranks have inward bends 58, Fig. 4, to bring the upper ends of the bell cranks into proximity to their respective operating slides 55; the arms 54 in said slides or actuators being preferably all vertical 80 (front view in Fig. 4), to agree with the vertical shifting of the segment, and the tops of the bell cranks also standing vertically at said Fig. 4. It will also be seen at 85 said figure, that the slides 55 are placed radially, and that the arms 54 are bent at corresponding angles to the bodies of the slides to bring the arms to vertical positions. The slides 55 occupy recesses or enlargements 59 in the radial type-bar slots 3, and lie side by 90 side with the type-bar hubs in the enlarged portions of the slots, as at Fig. 4; said slots therefore serving to guide the slides.

At Fig. 2^a, is seen a conformation of the lower portion of the segment 4, and a manner of mounting therein the type-bar fulcrum rod 2, as well as the front and rear curved rods 60, 61, upon which the slides 55 are guided; all of said rods being inserted in curved slots in the segment, the inner 100 ends of the slots being enlarged to fit the rods, and retain them in place. The type-bar operating slides 55 are provided with slots 62, 63, whereby they slide upon said 105 guide rods 60, 61; and these slots are preferably formed on a curve, as illustrated at Fig. 1, which is nearly concentric with the fulcrum 64 of the bell crank 51. This is done to give the slide a curvilinear motion, so that the wrist 56 thereon will have the desired action upon the connected type-bar; the direction of the movement of the wrist 56 being first along the slot 57, so that the type-bar is started slowly into motion, and then transversely of the slot, so that the 115 type-bar is speeded as it approaches the platen.

Variations may be resorted to within the scope of the invention, and portions of the improvements may be used without others. 120

Having thus described my invention, I claim:

1. The combination with a set of radially disposed type bars, and a shiftable segment or support therefor, of a set of sliding type-bar actuators mounted upon said support and having portions bent to the planes of the type-bars, and a set of key-operated levers having loose connections to said type-bar actuators. 125

2. The combination with a shiftable segment or support, of a set of type bars pivoted thereon and shiftable therewith, a set of slides mounted upon said support to shift therewith, said slides being bent at one end to the plane of the type bars and having connections at that end with the type bars, and a set of key-operated levers, said levers having connections with the unbent portions of said slides. 70
3. The combination with a shiftable segment or support, of a set of type bars pivoted thereon, a set of slides also mounted upon said support to shift therewith and connected to said type bars to operate the same, and a set of key-operated levers having loose connections to said slides to accommodate the shifting of said support; said slides having pin-and-slot connections 80 to said type bars, said levers, and said segment. 85
4. The combination of front strike type-bars, key-levers beneath the same, bell cranks or levers operated by the key-levers, radially mounted slides connected to the type-bars and bell cranks and having vertical slots to permit the type-bars and slides to shift for writing upper-case characters; a segment having radiating slots in which 90 said type-bars and slides are mounted, and said segment having a fulcrum rod for the type-bars, and also having curved guide rods for the slides. 95
5. The combination of front strike type-bars, key-levers beneath the same, bell cranks or levers operated by the key-levers, radially mounted slides connected to the type-bars and bell cranks and having vertical slots to permit the type-bars and slides to shift for writing upper-case characters; a segment having radiating slots in which 100 said type-bars and slides are mounted, said segment having a fulcrum rod for the type-bars, and also having curved guide rods for the slides, said slides having curved slots to engage said guide rods, and the type-bars having slots engaged by wrists on the slides, for the purpose set forth. 110
6. The combination of front strike type-bars, key-levers beneath the same, bell cranks or levers operated by the key levers, radially mounted slides connected to the type-bars and bell cranks and having vertical slots to permit the type-bars and slides 115 to shift for writing upper-case characters; a segment having radiating slots in which said type-bars and slides are mounted, and said segment having a fulcrum rod for the type-bars, and also having curved guide rods for the slides; said slots at their inner ends fitted to said type-bars, and at their outer ends recessed or widened to receive said slides. 120
7. The combination of a set of radiating front strike type-bars, a set of key-operated 125
- upstanding levers or arms below the type-bars, means to shift the set of type-bars, radially arranged slidable driving members connected to said type-bars and shiftable therewith, and having connecting arms for the key-operated levers, said members having portions bent to the planes of the type bars. 70
8. The combination of a set of radiating front strike type-bars, a set of key-operated upstanding levers or arms below the type-bars, means to shift the set of type-bars, radially arranged slidable driving members connected to said type-bars and shiftable therewith, and having connecting arms for the key-operated levers, said connecting arms extending in the direction of the shifting of the type-bar set, and having pin-and-slot connections to said key-operated levers, said members having portions bent to the planes of the type bars. 75
9. A type-bar segment provided with type-bar slots having recesses or enlargements at their outer ends, a curved fulcrum wire in the slots, type-bars fulcrumed on said wire in the slots, curved guide rods in said recesses, type-driving members in said recesses and guided on said rods, and means to actuate the type-driving members. 90
10. In a typewriting machine, the combination of a type-bar, a shiftable support therefor, a slidably oscillatable actuating member for the type-bar, guides for said member having curved slots in said member passing over said guides, a key lever connected to said member, and a vertically extensible joint in the connection between the lever and the member. 95
11. The combination in a typewriter, of a type-bar, a fulcrum rod therefor, a shiftable support for said rod, a slidably oscillatable type-bar actuating member mounted on said support having slots therein, guides engaged in said slots, a key-lever connected to said member, and an extensible joint in the connection between the lever and the member. 100
12. The combination of a type-bar, a support therefor, means to lift and lower the support, a slidably-movable type-bar actuating member, means connecting said member to the support and causing it to move up and down with the support, but permitting lateral movement of the member independently of the support, a key lever, and operating connections between the key lever and said member permitting the latter to move up and down without changing position of the key lever. 110
13. The combination of a type-bar, a support therefor, means to shift said support, a type-bar actuating member, means connecting said member to the support and causing it to move with the support during said shifting movement, but permitting movement of said member independently of the 115

support in a direction transverse to said shifting movement, a key lever, and operating connections between the key lever and said member permitting the said shifting movement of the said member without materially changing the position of the key lever.

14. In a typewriting machine, the combination of a type-bar, a slide connected to the type-bar to operate the same, a lever having a direct operating connection with the slide, said slide being formed with slots substantially in the arc of a circle having its center in the fulcrum of said lever, and guide pins 15 in said slots.

15. In a typewriting machine, the combination of a type-bar, a shiftable support in which the type-bar is fulcrumed, a slide carried by said support, and connected to the type-bar to operate the same, a lever, means to shift said support and slide toward and from the fulcrum of said lever, a slot and pin connection between the lever and said slide permitting such movement without 25 substantially varying the position of the lever, and means to guide said slide in an arc having its center of curvature at the fulcrum of said lever, and means to operate said lever and thereby actuate the type-bar.

16. In a typewriting machine, a sliding link having straight arms extending in opposite directions, and slotted curved arms extending in directions transverse to the straight arms.

17. In a type-bar action, a link having an upwardly extended arm, a depending slotted arm, and laterally extending slotted arms.

18. In a type-bar action, a slide, an upwardly extending arm, a wrist pin thereon, a downwardly extending arm having a straight slot, and laterally extending arms formed with arc-shaped slots having a center of curvature approximately in line with 45 said downwardly extending arm.

19. In a typewriting machine, a type-action comprising a type-bar, a slide having a slot-and-pin connection with the type-bar, a lever having a slot-and-pin connection with 50 the slide permitting the slide to move toward and from the fulcrum of the lever, means to operate said lever and impart a movement of translation to the slide, and means to guide the slide in such movement.

20. In a typewriting machine, the combination of a type-bar, a slide connected to operate the type-bar, a lever having a slot-and-pin connection with the slide, the slot being substantially in alinement with the 60 pin and the lever fulcrum, means to operate the lever, and means to guide the slide in an arc concentric with said lever fulcrum and permit a movement of translation when the lever is operated.

21. In a typewriting machine, the combi-

nation of a type-bar, a support therefor, a slide operatively connected to the type-bar and having a slot-and-pin connection with the support permitting movement of the slide in a direction to operate the type-bar, 70 the slide also having a slot substantially perpendicular to said direction of movement, a lever swinging in a plane inclined to that of the type-bar, a pin carried by the lever and engaging said last named slot, said slide being bent to bring its connecting portions into planes parallel respectively with the type-bar and said lever, and means to operate the said lever.

22. In a typewriting machine, the combination of a shiftable segment, type-bars pivotally supported thereon, slides having wrists working in slots formed in the type-bars, said slides having slots in alinement with said wrists, levers having wrists working in said last named slots, and guiding means permitting the slides to move bodily in a direction transverse to the said slots in the links but preventing movement of the links relatively to the segment in the direction of the slots.

23. In a typewriting machine, the combination with a set of type-bars, and a shiftable support therefor, of bodily movable type-bar slides or actuators slidable on the support, key-actuated levers having slot-and-pin connections with the slides, the slots extending in the direction of the shifting movement of the said support, said slides each formed with a plurality of guiding 100 slots transverse to the said direction of shifting movement, and guide rods carried in said support and extending through said guiding slots.

24. In a typewriting machine, the combination of a type-bar segment having radial slots, a fulcrum rod extending through the slots, type-bars fulcrumed on said rod, said slots being formed with recesses or widened portions, type-bar actuators overlapping the type-bars, the overlapping portions located in said recesses and operatively connected to the type-bars, and key-levers operatively connected to the actuators.

25. In a typewriting machine, the combination of a type-bar segment formed with radial slots having inner narrow portions and outer widened portions, type-bars fulcrumed in said narrow portions, type-bar actuators in the widened portions and overlapping the type-bars, said actuators being formed with slots, rods supported in the segment and extending through the slots in the actuators, key levers, and connections between the key levers and said actuators.

26. In a typewriting machine, the combination with a type-bar and a vertically shiftable support therefor, of a bell-crank lever having an upwardly extending arm and a horizontally disposed arm, a type-bar 130

actuator movable bodily in an arc having its center of curvature in the fulcrum of the said lever, said actuator being formed with a vertical slot and arc shaped slots, guides carried by the said supports extending through said curved slots in the actuator, a pin carried by said upwardly extending arm and engaging said vertical slot, and a horizontally disposed key-lever having a slot-and-pin connection with said horizontally disposed arm.

27. The combination of a type-bar segment provided with radially disposed slots, a curved fulcrum rod in the segment, type-bars extending into the slots and fulcrumed on said rod, slotted type-bar actuators also extending into the slots and overlapping the type-bars, curved rods extending through the slots in the actuators, key levers, and operating connections between the key levers and actuators.

28. The combination of front-strike radiating type-bars, key levers beneath the same, bell cranks or levers operated by the key levers, slides having radiating sections connected to the type-bars, said sections being bent to the planes of the type bars, and parallel sections connected to the bell cranks, said slides movable bodily in a direction to operate the type-bars and guides for said slides.

29. The combination of front-strike radiating type-bars, key levers beneath the same, bell cranks or levers operated by the key levers, and slides having radiating sections connected to the type bars and parallel sections connected to the bell cranks; said slides movable bodily in a direction to operate the type-bars, and having vertical slots to permit the type-bars and slides to shift for writing upper-case characters.

30. The combination with a shiftable segment or support, of a radially arranged set of type-bars pivoted thereon, a set of slides mounted upon said support to shift therewith and also slideable on the support, said slides having upright portions, and inclined portions connected to said type-bars to operate the same, and a set of key-operated levers having loose connections to said upright portions of the slides to accommodate the shifting of said support.

31. The combination with a shiftable segment or support, of a radially arranged set of type-bars pivoted thereon, a set of slides also mounted upon said support to shift therewith, said slides having upright portions, and inclined portions connected to said type-bars to operate the same, and a set of key-operated levers having loose connections to said upright portions of the slides to accommodate the shifting of said support; said slides having pin-and-slot connections to said type-bars, said levers, and said segment.

32. The combination of a set of radiating front-strike type-bars, a set of key-operated upstanding levers or arms below the type-bars, means to shift the set of type-bars, and radially arranged slideable driving members having inclined portions connected to said type-bars and shiftable therewith, and having upright connecting arms for the key-operated levers.

33. The combination of a set of radiating front-strike type-bars, a set of key-operated upstanding levers or arms below the type-bars, means to shift the set of type-bars, and radially arranged slideable driving members having inclined portions connected to said type-bars and shiftable therewith, and having upright connecting arms for the key-operated levers, said connecting arms extending in the direction of the shifting of the type-bar set, and having pin-and-slot connections to said key-operated levers.

34. In a typewriting machine, the combination of a type-bar, a support therefor shiftable in a direction inclined to the plane of movement of the type-bar, a slidably movable actuating member for the type-bar, guides for said member and a key-actuated lever operatively connected to said member, said member having portions parallel to the plane of the type-bar and other portions parallel to the direction in which said support is shiftable.

35. The combination in a typewriting machine, of a type-bar, a fulcrum rod therefor, a support for the said rod shiftable in a direction inclined to the plane in which the type-bar swings, a type-bar actuating member slidably mounted on said support, guides for said member and a key lever to operate said actuating member, said actuating member having a portion bent to be parallel to said plane and connected to the type-bar, and a portion bent to be parallel with the plane of the key lever and connected to the key lever.

36. The combination of a type-bar, a support therefor, means to lift and lower the support, said type-bar inclined to the direction in which the support moves, a type-bar actuating member having a portion parallel with and connected to the type-bar, means connecting said member to the support and causing it to move up and down with the support, but permitting lateral movement of the member independently of the support, a key lever, and operating connections between the key lever and said member permitting the latter to move up and down without changing the position of the key lever.

37. The combination of a type-bar, a support therefor, means to shift said support, said type-bar inclined to the direction in which the support moves, a type-bar actuating member having a portion parallel with

and connected to the type-bar, means connecting said member to the support and causing it to move with the support during said shifting movement, but permitting movement of said member independently of the support in a direction transverse to said shifting movement, a key lever, and operating connections between the key lever and

said member permitting the said shifting movement of the said member without materially changing the position of the key lever.

ALFRED G. F. KUROWSKI.
